L. J. BRUNE,
BURGLAR ALARM AND LATCH,
APPLICATION FILED NOV. 6, 1916.

1,227,994.

Patented May 29, 1917.

UNITED STATES PATENT OFFICE.

LOUIS J. BRUNE, OF ALGIERS, LOUISIANA.

BURGLAR-ALARM AND LATCH.

1,227,994.

Specification of Letters Patent. Patented May 29, 1917.

Application filed November 6, 1916. Serial No. 129,778.

To all whom it may concern:

Be it known that I, LOUIS J. BRUNE, a citizen of the United States, and resident of Algiers, in the parish of Orleans and 5 State of Louisiana, have invented certain new and useful Improvements in Burglar-Alarms and Latches, of which the following is a specification.

The present invention relates to new and 10 useful improvements in burglar alarms and the like, having as its primary object the provision of a novel and effective type of burglar alarm for detachable association with windows, doors and the like to warn 15 against unauthorized entrance by intruders.

Another object of my invention is to provide an alarm of the class described which may be readily attached to any existing sliding window or sliding door without altering 20 the construction of the door or window to which the device is applied.

A further object of my invention is to provide a device of the character described which will both lock the window and deliver 25 an alarm, the device permitting a window to be raised slightly but at the same time limiting the distance to which the same may be raised, and when repeated attempts are made to raise the window a succession of 30 alarms is given.

A still further object of my invention is to provide a latch and alarm actuating device of the class described which may be used in connection with any type of alarm either me- 35 chanical or electrical.

Other objects and advantages to be derived from the use of my improved burglar alarm and window latch will appear from the following detailed description and the 40 claims, taken with an inspection of the accompanying drawing, in which:

Figure 1 is a vertical sectional view, partly broken away showing a window frame and sashes and my invention applied in operative position;

Fig. 2 is a transverse sectional view taken on the line 2—2 of Fig. 1; and

Fig. 3 is a top plan view of the catch member.

Referring more particularly to the drawings, wherein similar characters of reference designate like and corresponding parts throughout the various views, 10 designates the window sill, 11 one of the side portions 55 of a window frame and 12 a window sash slideable in said frame.

The locking device comprises a circular plate 13 rotatably mounted on a screw 14, said screw being driven into the side member 11 as best shown in Figs. 1 and 2. A pair of 60 lugs 15 and 15' are carried by the plate 13, said lugs extending from the exposed face thereof to form guides for a sliding bolt 16, said bolt 16 having a lateral tapered enlargement 17 on one free end thereof. A coil 65 spring 18 encircles the bolt 16, said coil spring being interposed between the guide 15 and a pin 19 carried by said bolt whereby to normally tend to maintain the bolt in the outermost position. To maintain the bolt 70 16 against the action of the spring 18 I provide a hook 20 offset at 21 and pivotally mounted on the screw 14 as indicated at 22 in Fig. 2.

The hook 20 is arranged above the bolt 16 75 when the plate is applied in operative position, said hook 20 being moved into engagement with the free end of the bolt to maintain the same against movement.

A portion of the peripheral edge of the 80 plate 13 is recessed as at 23 to accommodate the free end of a stop-block 24, said block being secured to the side 11 of the window frame by means of screws 25 or the like. A catch member 26 is carried by the sash 35 and secured thereto by means of a screw or the like, said catch member having a tapered extension 27 to engage the tapered extension 17 on the bolt to maintain the window against upward movement. 90

A lug 28 extends radially from the plate 13, said lug being formed with an aperture 29 to receive the free end of a rod, cable or the like 30, the upper free end of the cable being connected to the hammer 31 of 95 a bell 32.

To lock the window the bolt is permitted to assume the position shown in Fig. 1 and when an attempt is made to raise the window the catch member 26 will engage with 100 the bolt, partially rotating the plate. This movement will actuate the hammer 31 of the bell 32 giving an alarm. When the block 24 reaches the opposite end of the recess 23 further upward movement of the window is impossible. I do not limit the application of the device in the exact position as shown, any convenient location on a window sash and window frame being taken. It is optional with the person installing 105 the device as to the distance between the catch member 26 and the bolt when in the 110

normal closed position. The device may be readily attached to any of the existing types of window frames without altering the construction of the window frame or sash. 5 The device will also be readily applicable for use in connection with sliding doors and the like.

From the above description taken in connection with the accompanying drawings, 10 it is thought that a clear and comprehensive understanding of the construction, operation and advantages of my invention may be had, and while I have shown and described the device as embodying a specific 15 structure, I desire that it be understood that such changes may be made in said structure as do not depart from the spirit and scope of the invention as claimed.

Having thus fully described my invention, what I claim as new and desire to secure by Letters Patent, is:—

1. In a window catch and alarm, the combination with a window frame and a sash 20 slideable therein, of a catch member carried by the sash, a plate rotatably mounted on 25 the frame, a lever slidably carried by the plate and having a lateral lug to engage the catch member, said lever being connected to

an alarm, and a hook carried by the plate to retain the lever, at times, from engagement with the catch. 30

2. In a window latch and alarm, the combination with a window frame and a sash 35 slideable therein, of a plate rotatably mounted on said frame, means to limit the movement of said plate, a spring actuated arm diametrically arranged on said plate, said arm having a lateral extension on the free end thereof, said plate being connected with an alarm device, a hook for restraining said 40 slideable member, and a catch member on the window sash to engage said slideable member.

3. In a window latch and alarm, the combination with a window frame and sash, 45 of a plate rotatably mounted in the frame, a sliding bolt carried by the plate, a spring to maintain the bolt in outermost position, a hook to retain the bolt, a catch member to engage one free end of the bolt, and an 50 alarm connected with said plate to be actuated by rotation of the same.

In testimony whereof, I affix my signature hereto.

LOUIS J. BRUNE.
